CLAIM

The ornamental design for a vacuum pump, as shown and described.

DESCRIPTION

1. Vacuum pump
- 1.1 : Perspective
- 1.2 : Perspective
- 1.3 : Perspective
- 1.4 : Perspective
- 1.5 : Perspective
- 1.6 : Perspective
- 1.7 : Perspective
- 1.8 : Perspective
- 1.9 : Front
- 1.10 : Back
- 1.11 : Right
- 1.12 : Left
- 1.13 : Top
- 1.14 : Bottom

The dot-dash broken lines appearing in the figures represent boundaries of the claimed design and form no part of the claimed design. The dash-dash broken lines appearing in the figures depict features of a vacuum pump that form no part of the claimed design.
